REINFORCED-FIBROUS-COMPOSITION SHEET.

1,201,756.

Specification of Letters Patent. Patented Oct. 17, 1916.

Application filed February 25, 1915. Serial No. 10,392.

To all whom it may concern:

Be it known that I, RAY P. PERRY, a citizen of the United States, residing in Montclair, New Jersey, have invented certain new and useful Improvements in Reinforced-Fibrous-Composition Sheets, of which the following is a specification.

This invention relates to the production of a reinforced fibrous composition sheet, suitable for roofing, siding and similar purposes and has for its object the economical production of sheets possessing the very desirable properties of this fibrous composition, including resistance to the elements coupled with stiffness and strength necessary to permit its use in sheets for siding and roofing in much the same way that sheet iron is now used. Metal will generally, but not necessarily, be used as the reinforcing material. The product is much cheaper than plain or galvanized sheet iron and at the same time possesses greater resistance to action of the elements than does the plain sheet iron, and in some cases has greater wearing properties than even the galvanized sheet iron.

In the patent of James C. Woodley, No. 1,156,122, dated October 12, 1915, for fibrous composition and process of manufacture is described the composition and method of manufacture of the fibrous composition which is preferably used in connection with suitable reinforcing. This reinforcing may take the form of metal wire mesh or of expanded metal, or of thin perforated sheets of metal, the word "reticulated" being used to include all these and equivalent constructions. The fibrous composition serves to protect from the elements the metal base, which is ordinarily ungalvanized, and at the same time in the case of wire mesh or perforated or expanded metal, serves to fill the web, making a finished sheet having the required stiffness and other properties for the purposes in hand. The product may be supplied in flat sheets or in many cases it is preferable to supply them corrugated, in the same way that sheet iron is corrugated. These sheets may be of any desired thickness, width and length.

It has been previously proposed to make felt roofing in corrugated sheets composed of two or more sheets of felt and an intermediate interstitial web of metal but such prod-

uct only contemplated the use of previously prepared sheets of felt, whereas the present product does not consist of separate sheets of felt but of a fibrous composition which is homogeneous throughout and forms one uniform body in which the metal reinforcing is embedded. The sheets of felt heretofore proposed would have very much less durability, as such felt at best can only be imperfectly saturated and on exposure to the weather would go to pieces rapidly. If such felt were covered with a thin superficial coating of bituminous material this coating would, after a short time, become punctured or worn off and then the felt would be presented to the destructive action of the elements.

My invention will for the purposes of illustration be described in its adaptation to making corrugated sheets for roofing purposes. In the first place, the fibrous composition is prepared by introducing say twenty parts by weight of fibrous material, such as waste paper, to eighty parts of binder, such as asphalt or pitch of the desired consistency, and then disintegrating the fibrous material without destroying its fibrous nature, so that the fibers are distributed substantially homogeneously throughout the binder and are coated and cemented together and in some cases saturated by the binder, yielding a tough, fibrous composition.

The preferred method of forming the product is to introduce a wire mesh between a pair of compression rolls and at the same time place some of the above-described fibrous composition on each side of the wire mesh in such a manner that as the rolls revolve they draw forward the wire mesh and at the same time the fibrous composition on each face thereof and cause the wire mesh to be embedded in the fibrous composition and coated on both faces with same. In some cases it may be advantageous to perform this operation with two sets of such rolls as the product from the first set may not give a perfectly uniform sheet and we may then lead this imperfectly formed sheet to a second set where a further supply of the fibrous composition is introduced and perfects the sheet as delivered. Or the composition may first be passed between rolls or in any other desired way formed into sheets; which sheets, with the wire mesh be-

tween them, are passed between compression rolls, at suitable temperature, and by pressure of the rolls are united into one homogeneous sheet in which the wire mesh is 5 embedded.

The sheet coming from the compression rolls is cut to the desired length and we may secure in this way sheets say eight feet or 10 ten feet long and perhaps thirty-six inches wide. These sheets are then passed between corrugating rolls of the type usually employed with roofing sheets and corrugated to the desired pitch.

We may, if desired, omit the corrugating 15 process and ordinarily would do this if we used expanded metal for the reinforcing. The corrugating serves in general to increase the stiffness and strength of the product.

20 The accompanying drawings illustrate the process and product in connection with suitable apparatus.

Figure 1 is a cross-section and Fig. 2 a 25 side elevation showing the making of the product from previously unformed masses of roofing composition; Fig. 3 is a cross-section showing the making of the product from masses of the composition which have been previously converted into the form of 30 sheets; Fig. 4 is a schematic view illustrating the product in section on an enlarged scale.

The rolls A are the compression rolls 35 which form the product and which revolve in the directions indicated by the arrows. The rolls B are arranged in advance of the compression rolls and serve to straighten the wire screen C which is passed between them and down into the space between the 40 forming rolls A. The wire screen is supplied on a roll D whence it is carried down between the rolls A and B, as shown. The fibrous composition is supplied in unformed 45 masses E at such temperature as to be suitably plastic. Such a mass of fibrous composition is applied to both sides of the wire screen C and is caught and carried down by the rolls A and compressed between them, carrying the wire screen along so that the latter is embedded in the product F. The 50 fibers in the composition, while adherent to each other by reason of the bituminous binder, are not permanently attached to each other and are thus free to be forced into the meshes of the wire screen in the manner indicated in Fig. 4, so that the masses E do 55 not remain separate on opposite faces of the screen, but are united so as to form practically a single layer or sheet of fibrous composition coating both faces of the screen which is embedded therein and to a degree interlaced with the fibers.

60 For greater convenience in handling the fibrous composition and for more accurately determining the quantities thereof on opposite sides of the sheet such composition may

be first formed into sheets E' (Fig. 3) which are carried from rolls G and over idlers H to the space between the compression and forming rolls A; the wire screen being handled the same as in Fig. 1. The sheets 70 E' must be of such composition and at such a temperature as to be quite plastic and to permit the compression and forcing of the fibers into the meshes of the reinforce as above described.

75 Fig. 1 shows the sheet F passed through a second set of compressing and forming rolls A' with additional quantities or masses E of fibrous composition applied to the sides as desired to perfect the product in the matter 80 of thickness of the composition on opposite sides, and to additionally compress it if that be desired.

The fibrous composition may be of the natural color or be artificially colored, or 85 that supplied to one face only may be artificially colored, or the composition applied to one face may be of a different grade from that supplied to the other. Similarly the composition supplied to the second set of 90 rolls A' may be different from that supplied to the first set and may be artificially colored on one or on both sides so as to produce a product having a veneer of colored material. This method of coloring the sheets is described in full and claimed in an application 95 of mine pending concurrently herewith.

Though I have described with great particularity of detail certain specific embodiments of my invention, yet it is not to be 100 understood therefrom that the invention is restricted to the particular embodiments disclosed. Various modifications thereof may be made by those skilled in the art without departure from the invention.

105 What I claim is—

1. A reinforced fibrous composition sheet comprising a reticulated reinforce embedded in a body of fibrous composition consisting of a bituminous binding material and 110 elementary fibers distributed substantially uniformly and homogeneously throughout the mass and separately and thoroughly coated with the binder and interlaced or 115 felted together, the proportions being such as to render the composition non-liquefiable by heat, said fibrous composition passing through the meshes of the reinforce.

2. A reinforced fibrous composition sheet comprising a reticulated reinforce embedded in a body of fibrous composition comprising fibers of paper coated with bituminous material and adherent but not permanently attached to one another, said fibrous composition passing through the meshes of 120 the reinforce.

3. A reinforced fibrous composition sheet comprising a reticulated reinforce embedded in a body of fibrous composition consisting of paper fibers coated with pitch and 125 130

adherent but not permanently attached to one another, said fibrous composition passing through the meshes of the reinforce.

4. A reinforced fibrous composition sheet comprising fibers coated with bituminous material and adherent but not permanently attached to one another, the proportions being such as to render the composition non-liquefiable by heat, said fibrous composition passing through the meshes of the reinforce.

5. A reinforced fibrous composition sheet comprising fibers coated with pitch and ad-

herent but not permanently attached to one another, the proportions being such as to render the composition non-liquefiable by heat, said fibrous composition passing through the meshes of the reinforce. 15

In witness whereof, I have hereunto signed my name in the presence of two subscribing witnesses.
